UNITED STATES PATENT OFFICE.

GUST WIITALA, OF ONTONAGON, MICHIGAN.

LOCK.

1,134,791.

Specification of Letters Patent.

Patented Apr. 6, 1915.

Application filed December 13, 1913. Serial No. 806,572.

To all whom it may concern:

Be it known that I, GUST WIITALA, a citizen of the United States, residing at Ontonagon, in the county of Ontonagon and 5 State of Michigan, have invented new and useful Improvements in Locks, of which the following is a specification.

The invention provides a lock, the key-hole of which is normally closed by means 10 of a guard, the latter being held in normal position by locking means which is of a nature embodying a device required to be manipulated by hand in order to bring the locking elements in such relation as to admit of their movement to release the guard 15 before the latter may be moved to uncover the keyhole so that the key may be introduced into the lock.

The invention further provides a lock embodying a supplemental lock bolt which is 20 adapted to be actuated by means of a spindle, said spindle being accessible and operable only when the guard is moved to a predetermined position so as to uncover a 25 finger piece which automatically springs into position to be conveniently grasped for throwing the supplemental lock bolt. When the supplemental lock bolt is shot into locking position it is absolutely necessary to 30 throw the same before the part to which the lock is attached may be opened even though the main lock bolt is thrown. The supplemental lock bolt is adapted to be operated by means of a spindle forming a part 35 of the lock mechanism in contradistinction to the main lock bolt which is key operated.

The invention consists of the novel features, details of construction and combination of parts, which hereinafter will be more 40 particularly set forth, illustrated in the accompanying drawings and pointed out in the appended claims.

Figure 1 is a view in elevation of a lock embodying the invention. Fig. 2 is a side 45 view of the lock with the guard plate moved so as to uncover the keyhole. Fig. 3 is a view similar to Fig. 2 showing the guard plate moved farther so as to expose the finger piece, whereby the spindle is operated 50 for throwing the supplemental lock bolt. Fig. 4 is a view in elevation having the removable plate closing the open side of the lock case omitted. Fig. 5 is a transverse section on the line 5—5 of Fig. 4. Fig. 6 55 is a horizontal section on the line 6—6 of Fig. 4. Fig. 7 is a detail view of the side

plate of the lock case showing the keyhole, the key arbor in end elevation and the pressure block held yieldingly against the flat sides of the key arbor to hold the same in 60 normal position. Fig. 8 is a detail view of a part of the guard plate having the recess for receiving the raised part of the lock pin tumbler and having the oblong opening in which the lock pin operates. Fig. 9 is a 65 view in elevation of the reverse side of the lock pin tumbler showing the ratchet and the yieldable detents for cooperation with the lock pin. Fig. 10 is an enlarged section on the line 23—23 of Fig. 3. Fig. 11 is an 70 enlarged section on the line 24—24 of Fig. 1 of one side of the lock case and the parts attached thereto. Fig. 12 is an enlarged view of the lock pin tumbler showing the lock pin in section and the pressure blocks 75 for retaining such lock pin in the desired position. Fig. 13 is an enlarged section on the line 26—26 of Fig. 22.

Corresponding and like parts are referred to in the following description and indicated in all the views of the drawings by the same reference characters.

The numeral 1 designates the lock case which houses the working parts and which may be of any construction or finish according to the character of the lock in its marketable form. One side of the lock case is open to admit of access to the interior thereof for placing the working parts in position or to admit of access to such parts 85 for repairs. A plate 2 closes the open side of the case. The keyhole 3 is formed in the side plates of the case and such keyhole has its eye enlarged to receive the reduced end 4 of the key arbor 5, the latter being journaled in the side plates of the case and having opposite side portions of its rounded ends cut away to form flat faces 6 against which pressure blocks 7 are adopted to bear 90 so as to hold the key arbor in normal position. The pressure blocks 7 as well as their springs 8 are located in recesses 9 formed in the outer faces of the side plates of the lock case. The body portion of the key arbor fits between the side plates of the lock case 95 and has a slot along one side for the passage of the nib of the key, said passage corresponding with the slot of the keyhole 3. The main lock bolt 10 is preferably located in the lower portion of the lock case and is 100 adapted to be thrown by means of a key. The supplemental lock bolt 11 is located in 110

the upper portion of the lock case and is adapted to be thrown by means of a spindle 12 which is journaled at its ends in the side plates of the lock case, said spindle having 5 a toothed portion 13 in mesh with a toothed portion 14 of the lock bolt. The inner end of the lock bolt 11 is supported and directed in its movements by means of a post 15. The spindle 12 is formed with a centrally disposed longitudinal opening in which a 10 pin 16 is adapted to move, said pin having a head at its inner end against which an expansible helical spring 17 exerts a pressure to force the pin 16 outward. A finger piece 15 18 is connected with the outer end of the pin 16 and serves as means for rotating the spindle when it is required to throw the bolt 11 either into locked position or to 20 retract the same. The pin 16 formed at its inner end with a head is of noncircular form in cross section which operates within the spindle and causes it to rotate when the pin is turned. The finger piece 18 normally occupies a position in a recess 19 25 formed in a cover plate 20 arranged exterior to the side plate 2. A guard plate 21 arranged exterior to the cover plate 20 is intended to conceal the keyhole and extend over the finger piece 18 and hold the same 30 repressed against the action of the spring 17. When the guard plate 21 is moved so as to clear the finger piece 18, as indicated in Fig. 3, said finger piece springs outward 35 into a convenient position to be grasped so that the spindle 12 may be turned to admit of throwing the supplemental lock bolt in either position. When the lock is in position it is arranged with the open side facing outward and the closed side facing inward 40 or located adjacent the door or like part to which the lock is attached. It follows therefore that the guard plate 21 is located against the outer side of the lock case. The inner cover plate 20 extends over the recess 45 9 and the parts 7 and 8 located in such recess. The usual keyhole guard 22 is pivoted to the plate 20.

The guard plate 21 is movable on the lock case and carries a lock pin 23 which is arranged to operate in a slot formed in the outer cover plate 20. The lock pin 23 is provided at its outer end with a knob 24 and its inner end is formed with a head 25 which is arranged to operate in a recess 26 50 formed in the outer side of the plate 2. The recess 26 conforms approximately to the outline of the slot formed in the plate 20. This slot comprises a longitudinal portion 27, a vertical portion 28 at one end thereof and an off-set portion 29 at the opposite end. The off-set portion 29 of the slot is located at the inner end and is interrupted by means of a projection 30. The guard plate has a circular recess 31 in its outer 55 side and a vertical elongated opening 32

which is adapted to register with the vertical portion 28 and an off-set portion 29 of the slot formed in the plate 20. The lock pin 23 passes through the opening 32. A tumbler 33 is mounted upon the guard plate 21 and has a raised portion fitting within the circular recess 31, said raised portion having teeth 34 around its outer edge to be engaged by means of a dog 35 located upon the plate 21 at one side of the recess 31. An 60 elongated opening 36 is formed in the tumbler 33 and receives the lock pin 23 which passes therethrough. When the tumbler 33 occupies a position with its opening 36 in register with the opening 32 and the vertical portion 28 of the slot formed in the cover plate 20 the lock pin may be moved so as to aline with the longitudinal portion 27 of the slot, thereby admitting of the guard plate 21 being moved so as to uncover 65 the keyhole as indicated most clearly in Fig. 2. When the lock pin 23 reaches a point to engage with the projection 30 the keyhole 3 is uncovered but the finger piece 18 remains hidden from use. To disclose the finger piece it is necessary to move the lock pin 23 upward in the off-set portion 29 of the slot thence over such projection and again downward in the rear thereof, and during such movement the guard plate traverses a distance to uncover the finger piece 18 which springs outward from the recess 19 into position to be conveniently grasped 70 for rotating the spindle 12 for throwing the bolt 11. The finger piece 18 is oblong and the recess 19 is of corresponding shape hence when the finger piece is held within the recess 19 the spindle 12 and lock bolt 11 are held secure against movement. When the guard plate is in the position indicated 75 in Fig. 1 and the knob 24 is moved to aline with the tumbler 33 the lock pin 23 occupies a position at the upper end of the vertical portion 28 of the lock pin slot and upon turning the tumbler 33 to throw the 80 opening 36 out of line with the opening 32 the lock pin is retained in the upper portion of the slot 28 thereby preventing any movement of the guard plate. As indicated most clearly in Fig. 1 an indicating mark is provided upon the guard plate 21 adjacent the recess 31 and the edge of the tumbler bears a plurality of marks one of which when brought in line with the indicating mark on the plate 21 brings the opening 36 of the 85 lock pin tumbler 33 in register with the opening 32 so that the lock pin may be moved from the vertical portion into the horizontal portion of the lock pin slot preliminary to moving the guard plate inward or uncovering the keyhole and the finger piece of the spindle supporting pin 16. The lock pin 23 is held at either end of the vertical portion 28 of the lock pin slot by 90 means of yieldable detents 37, the latter 95

consisting of short bars located upon opposite sides of the opening 36 and held pressed outward toward each other by means of springs 38. Each of the detents 37 is formed upon its outer side with a projection 39 which slopes in opposite directions toward the ends of the detents. The projections 39 extend inward beyond the vertical edges of the opening 36 so as to engage the lock pin 23 and hold it in the required position until sufficient force is applied to move the lock pin in the opening 36 by the projections 39. It will be understood from the foregoing taken in connection with the accompanying drawings that there is a mutual cooperation between the specific form of key and the particular form of lock mechanism and that each is dependent upon the other for successful operation of the lock. It being assumed that both the main and supplemental lock bolts are projected and it is required to open the lock pin tumbler 33 is turned until the proper indicating mark comes opposite the indicating mark on the guard plate, thereby bringing the opening 36 in register with the opening 32 after which the knob 24 is pressed downward to carry the lock pin 36 from the upper end of the vertical part 28 of the lock pin slot into the lower end of such slot in line with the horizontal part 27. The guard plate 21 being released may be moved inward, the lock pin 23 traveling in the horizontal portion 27 of the lock pin slot. When the lock pin 35 strikes the projection 30 the keyhole of the lock is uncovered. If it be desired to first withdraw the supplemental lock bolt 11 the lock pin is moved upward in the offset portion 29 of the lock pin slot thence along the off set portion 29 of the lock pin slot and down in rear of the projection 30. This brings the guard plate into the position indicated in Fig. 3 with the finger piece 18 of the spindle operating pin 16 in position to 45 be grasped and by rotating the spindle the lock bolt 11 is withdrawn.

Having thus described the invention what is claimed as new, is:—

1. In a lock, the combination of a lock bolt, a spindle for throwing the lock bolt, spindle operating means adapted to be moved outward or pressed inward, a spring normally exerting a pressure upon the spindle operating means to throw the same outward, a guard adapted to extend over the spindle operating means and hold the same pressed inward, and locking means for securing the guard.

2. In a lock, the combination of a lock bolt, a spindle for throwing such bolt, a finger piece for operating the spindle and adapted to be moved outward or pressed inward, a spring for pressing the finger piece outward, means for engaging the finger piece when pressed inward to prevent rota-

tion thereof, a guard for holding the finger piece inward and means for securing such guard.

3. In a lock, the combination of a lock bolt, a toothed portion formed on said lock bolt, a spindle, a toothed portion formed on said spindle in mesh with the toothed portion of the lock bolt, actuating means for the spindle having a sliding connection therewith, a spring normally exerting a pressure to throw the spindle actuating means outward, and means engaging the spindle actuating means for sealing and holding the same pressed inward.

4. In a lock, the combination of a lock case comprising a plate having a slot comprising longitudinal portions, a guard plate slidable upon the lock case and having a vertically elongated opening, a lock pin passing through the opening of the guard plate and the slot in the plate of the lock case, a rotary tumbler mounted upon the guard plate and having an oblong opening to register with the opening of the guard plate, and the slot in the plate of the lock case and a lock pin passing through the openings of the tumbler and guard plate and slot in the plate of the lock case, said lock pin being held in locked engagement with the guard plate and plate of the lock case by means of the tumbler.

5. In a lock, the combination of a lock case embodying a plate having a groove therein, a projection, a cover plate having a slot which is provided at one end with a vertical portion and at its opposite end with an off-set portion into which extends said projection, said slot being arranged opposite the groove in the plate of the lock case, a guard plate slidable upon the cover plate and having a vertically elongated opening to register with the vertical portion of the slot in the cover plate, a lock pin passing through the opening of the guard plate and the slot of the cover plate and a rotary tumbler mounted upon the guard plate and having an elongated opening to receive the lock pin.

6. In combination, a lock having main and supplemental lock bars, one of such lock bars being key operated, a manually operable spindle for throwing the other lock bolt, a guard plate for covering the key hole and the said manually operable spindle, and locking means between the guard plate and lock casing adapted to be intermittently operated to arrest the movement of the guard plate when first moved to uncover the key hole and adapted to admit of a further movement of the guard plate to uncover the said manually operable spindle.

7. In combination, a lock comprising a lock case having a side plate in which is formed a recess, a projection, a cover plate having a longitudinal slot provided at one

4

end with a vertical portion and at its opposite end with an off-set portion into which extends said projection, a guard plate slideable on the cover plate and having a vertically elongated opening, a lock pin passing through the opening of the guard plate and slot of the cover plate, a head at the inner end of the pin arranged to operate in the recess in the side plate of the lock case, a knob 10 at the outer end of the lock pin and rotary

tumbler mounted upon the guard plate and having an elongated opening to receive the said lock pin.

In testimony whereof I affix my signature in presence of two witnesses.

GUST WIITALA.
